Primary Examiner — S. Bryan Reinholdt, Jr.

(57) **CLAIM**

The ornamental design for a raised planter, as shown and described.

DESCRIPTION

FIG. 1 is a front and top perspective view of a raised planter, showing my new design;

FIG. 2 is a front and bottom perspective view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion, labeled '9' of FIG. 1; and,

FIG. 10 is an enlarged view of the portion, labeled '10' of FIG. 1.

The evenly spaced broken lines depict portions of the raised planter in which the design is embodied that form no part of the claimed design. The short dash-long dash broken lines depict the boundaries of the enlargements that form no part of the claimed design.

1 Claim, 10 Drawing Sheets(56)
